Frederick W. Hays
ATTORNEY.

UNITED STATES PATENT OFFICE.

ELMER E. FREY, OF LONG BEACH, CALIFORNIA, ASSIGNOR TO LOS ANGELES BOOK MACHINE COMPANY, OF LOS ANGELES, CALIFORNIA, A CORPORATION OF CALIFORNIA.

MACHINE FOR MAKING BOOKS.

Application filed January 12, 1921, Serial No. 436,790. Renewed March 13, 1923.

To all whom it may concern:

Be it known that I, ELMER E. FREY, a citizen of the United States, residing at Long Beach, in the county of Los Angeles and 5 State of California, have invented a new and useful Machine for Making Books, of which the following is a specification.

This invention relates to a machine for making books and is particularly directed to 10 means for securing together the several signatures comprising a book.

The object of the invention is to provide a machine which will assemble the signatures to form a book and which will successfully staple the signatures together as they are assembled.

Various other objects and advantages will be more fully apparent from the following description of the accompanying drawings, 20 which form a part of this disclosure, and which illustrate a preferred form of embodiment of the invention.

Of the drawings:

Figure 1 is a top plan view of the machine.

Fig. 2 is a right side elevation.

Fig. 3 is a top plan view with the table and magazine removed.

Fig. 4 is an enlarged vertical section on 30 line x^4-x^4 of Fig. 1.

Fig. 5 is a front elevation of the mechanism shown in Fig. 3, some of the parts of the rear portion of the machine being omitted for the sake of clearness.

Fig. 6 is a rear elevation of one of the 35 stapling heads.

Fig. 7 is an enlarged vertical section on line x^7-x^7 of Fig. 6.

Fig. 8 is a plan section on line x^8-x^8 of 40 Fig. 7.

Fig. 9 is a plan view of a stapling head.

Fig. 10 is a fragmentary section on line $x^{10}-x^{10}$ of Fig. 8 with the wire stock removed.

Fig. 11 is a plan view of one pair of anvil arms, with their operating cams shown in section.

Fig. 12 is a vertical section on line $x^{12}-x^{12}$ of Fig. 11.

Fig. 13 is a vertical section on line $x^{13}-x^{13}$ of Fig. 11.

Fig. 14 is a plan view of the stapling head operating mechanism, with the cam shown in section.

Fig. 15 is a side elevation of the mechanism shown in Fig. 14. 65

Fig. 16 is a plan view of the shifting mechanism for the stapling heads.

Fig. 17 is a detached view of one of the picker fingers and its operating cam. 60

Fig. 18 is a detached plan view of one pair of anvil arms and an associated stapling head, with one position of said head designated by dotted lines.

Fig. 19 is an elevation of the back edge 65 of a finished book.

Fig. 20 is a semi-diagrammatic view showing the book signatures stapled together and with the several signatures stretched apart to illustrate the operation of attaching the signatures together. 70

Fig. 21 is a section on line $x^{21}-x^{21}$ of Fig. 20.

In its broadest aspect the machine of the present invention is adapted to be used in securing each succeeding section to only the adjacent preceding section. The term section as herein used will be understood to designate a single signature of ordinary thickness or several thinner signatures, the thickness of the sections depending upon the size of staples used in attaching the sections together. For instance, if a book is printed on thin paper of, say, eight page signatures, 75 said signatures may be so thin that it would be impractical or undesirable to staple each signature separately to the adjacent signature. In this case it is contemplated to assemble and staple more than a single signature in each step of the book forming operation.

Therefore, I have used the term "section" to designate a unit of uniform thickness which in some instances may comprise a single signature or a plurality of attached leaves and in other instances may comprise a plurality of signatures. 80 85 90

In the drawings, the book shown is formed of sections each comprising a single relatively thick signature and in the following description I will refer to said sections as signatures although with the above explanation it will be understood this is done only to facilitate a clear understanding of the specific form illustrated in the drawings. 100

Referring to Figs. 19, 20, 21 of the drawings, the book is illustrated as comprised of a plurality of signatures 1 assembled in their order of sequence and secured together 105

at or near their back edges preparatory to binding.

In Fig. 20 the several signatures are shown in semi-diagrammatic form, the signatures being spread apart to show the relative locations of the attaching staples, which in the book shown are disposed in three groups with each group consisting of two rows of staples, the staples of one row being staggered relative to those of the adjacent row.

The several groups of staples are spaced from each other such distances as the nature of the book and experience will determine, it being understood that the number of such groups will depend upon the length of the binding edge of the book.

With reference to Fig. 20, the signature 1^b, for example, may be referred to as that which has already been assembled and attached to the preceding signature 1^a by the staples 2^a. In the next operation the succeeding signature 1^c will be assembled and stapled to the preceding signature 1^b by the staples 2^b.

Successively the signature 1^d will be assembled and attached to the signature 1^c by the staples 2^c which are aligned with the staples 2^a, and the signature 1^e will be assembled and attached to the preceding signature 1^d by the staples 2^d which are aligned with the staples 2^b, and this sequence of operations will be repeated throughout the forming of the entire book.

By this series of operations I am able to form a book of any thickness with the several book sections or signatures attached together by wire staples whereas by previous book stapling operations the thickness of the book is limited by the thickness of material through which a single staple can be driven.

The machine for making books by the above described operations, consists generally of means for successively assembling the signatures and of means, operating in timed relation to the assembling mechanism, for forming, driving and clinching the staples.

The various operating mechanisms of the machine are supported between two vertical side frames 10 and beneath a horizontal table plate 11 which extends between the upper ends of the side frames. To the rear of and above the table is a magazine for receiving the loose signatures 1. Said magazine comprises a floor plate 12 supported on brackets 13 attached to the side frames, a horizontal abutment bar 14 extending across the machine above the forward edge of the floor plate 12 and supported on brackets 15 projecting upwardly from the side frames, and a follower 16 slidable on the floor plate 12 and on guide rods 17 projecting horizontally rearward from and attached to the top portions of the

brackets 15. To each of the brackets 15 is attached one end of a cable 18 which extends rearwardly and is passed over a sheave 19 journaled on the follower and to the free end of the cable is attached a weight 20. By this arrangement the follower 16 exerts a forward pressure on the signatures to keep the signature pack pressed against the abutment bar 14. The floor plate 12 extends forward to a point slightly rearward of the abutment bar 14 (see Fig. 4) so that the first signature of the pack can be drawn downwardly by suitable devices hereafter described. Slidable on the table is a block 21 having a rear vertical face against which the formed book engages, said block being relatively heavy and having studs 22 projecting into slots 23 in the table to guide the block. Said block may aptly be termed a resistance block in that it offers resistance to the feeding movement of the book.

In general terms the operating mechanism comprises vertically movable picker bars 25 which move upwardly to engage the first signature of the pack and then downwardly to bring said signature to the table level in position for attachment to the book being formed, anvil bars 26-26^a which have a compound vertical and horizontal movement from a position between the signatures of the book to a position in front of the last clinched staple, oscillating stapling heads 27 having wire feeding and staple forming means; and oscillating driving bars 28-29, the bar 28 carrying the stapling heads 27 forward and operating the wire cutting and staple forming means of said heads and the bar 29 operating the staple driving and wire feeding means.

The several mechanisms are operated in timed relation by suitable cams on a main drive shaft 30 and a secondary drive shaft 31 journaled in the side frames 10.

Referring particularly to Figs. 2, 3, any suitable driving device, such as an electric motor, may be utilized to drive the gear 32 which has fixed to it a smaller gear 33, both gears being journaled on a stud shaft 34 fixed in the right hand side frame 10. The gear 33 meshes with a gear 35 keyed to the main drive shaft 30 and just inside the opposite side frame (see Fig. 5) the shaft 30 has fixed thereto a gear 36 which meshes with a gear 37 fixed to the secondary drive shaft 31, the gears 36-37 being of two to one ratio so that the shaft 30 makes two revolutions to one revolution of the shaft 31.

The machine illustrated in the drawings is designed to form books having four groups of staples and is provided with four pairs of anvil arms 26-26^a and four stapling heads 27 and in the operation said heads shift laterally to bring them first into cooperative alignment with the arms 120

26 and then into cooperative alignment with the arms 26^a in continuous alternation throughout the making of the books. As shown in Figs. 1 and 4, the rear edge of the 5 table is formed of an angle iron 40 providing a solid abutment against which the several anvil members engage. Secured to the under surface of the table adjacent its rear edge I provide two transversely adjustable 10 stop fingers 41—41 extending rearwardly of the table with their top surfaces flush with the top surface of the table. The fingers extend rearwardly beyond the forward edge of the floor of the magazine and the signatures 15 are drawn down to rest upon them in position to be attached to the book. The mechanism for successively drawing the signatures from the magazine downwardly upon the stop fingers 41 includes the two 20 picker bars 25 which are carried by a cross rod 42 extending through vertical slots 43 in each side frame 10, the outer end of the rod 42 beyond the left hand side frame engaging in a slot 44 in one end of an operating bell-crank lever 45 (see Fig. 17). The lever 45 is pivoted on a stud 46 on said side frame and carries a roller 47 engaging a cam 48 fixed on the main shaft 30, a spring 49 maintaining the roller in contact with 25 the cam. By this arrangement the picker arms 25 will be elevated and retracted once during each rotation of the shaft 30. Each of the picker arms 25 have a pair of opposed spring fingers 50 secured in their upper ends and contoured to form a diverging throat between the fingers and each arm 25 has an elongated slot 51 engaging a stationary cross rod 52 to guide the arms in a vertical plane during their movements. The 30 throat formed by the spring picker fingers 50 is in vertical alignment with the edge of the first signature in the magazine and the picker arms are first elevated to project the picker fingers 50 on opposite sides of said signature with the signature wedging into the throat, the picker arms then being retracted to carry the engaged signature down upon the stop fingers 41 with the retracting movement continuing to disengage the picker fingers 50 from the signature, 35 leaving the signature in assembled position ready to be attached to the book.

The anvil bars 26—26^a each have an anvil blade 55 which forms a backing against which the staples are driven and the upper rear surface of said blade is grooved, as at 56, (see Figs. 7—8) to provide means for clinching the free ends of the staples. With 40 particular reference to Figs. 3, 11, 12, 13, it will be noted that the anvils are arranged in pairs and by reference to Fig. 20 it will be explained that the anvil bar 26 functions only in the driving and clinching of the one row of staples 2^a—2^a, etc., and the anvil bar 26^a functions only in the driving and clinch-

ing of the row of staples 2^b—2^b, etc. Therefore, it will be evident that the anvil bars 26—26^a will be alternately operated in stepped movements. The particular sequence of the operations of the anvil arms, as diagrammatically shown in Fig. 20 will be explained before going into the details of the operating mechanisms. Assuming that the anvil arms 26—26^a are in the positions shown in dotted lines and the staple 2^f has 5 been driven by the stapling head to attach the signature 1^g to the signature 1^f; the anvil 26^a is then withdrawn from between the signatures 1^e and 1^f and projected in rear of the staple 2^f. Next, the signature 1^h is compiled and the stapling head shifted laterally into alignment with the anvil 26 and is operated to drive the staple 2^g, attaching the signature 1^h to the signature 1^g. The anvil 26 is then withdrawn from between the signatures 1^f—1^g and inserted in rear of the staple 2^g in position for the clinching of the next succeeding aligned staple. The stapling head is again shifted laterally and the signature 1ⁱ compiled and stapled to the signature 1^h, this sequence being repeated throughout the formation of the entire book. As each anvil arm is projected upwardly it also moves to contact the rear edge of the table and in so doing it feeds the book along the table against the resistance offered by the resistance block 21. 60

Referring particularly to Figs. 3, 4, 11, 12, 13, each anvil arm 26 is pivotally connected to the rear end of a rock lever 58 and each anvil arm 26^a is pivotally connected to the rear end of a similar rock lever 59, and between each anvil arm and its companion rock lever is a coil spring 60 exerting a circular tension tending to maintain the rear edge of the anvil bar in sliding contact with a stationary transverse rod 61, one end of said spring being connected to the anvil arm and the other end to the rock lever. 100

Each pair of rock levers 58—59 are loosely journaled on a rod 62 and are maintained in relative spaced relation by an intermediate spacing sleeve 63 (see Fig. 11) and are maintained against axial movement on the rod by opposed collars 64 secured on said rod. The forwardly projecting ends of the rock levers support relatively opposed anti-friction rollers 65—66 each engaging into a respective cam groove of a double cam 67 keyed on the secondary shaft 31. The formations of the respective cam grooves of the cam 67 are such that the anvil arms 26—26^a are alternately operated in the sequence previously described. 110

The rear edges of each anvil arm is cut away to form a cam shoulder 68 which is located above the rod 61 when the anvil arm is in elevated position. When said arm is retracted the cam shoulder 68 will be car- 125

ried below the rod 61 permitting the anvil arm to be propelled rearwardly by the spring 60 so that upon the subsequent elevation of the arm its anvil blade 55 is 5 carried upwardly in rear of the book and then moved forwardly by the engagement of the cam shoulder 68 with the rod 61 to feed the book forward and bring said blade 55 again into abutting engagement with 10 the angle iron 40 which forms the rear edge of the table.

The stapling heads 27 are clamped in relative spaced relation on a rock shaft 70 by set screws which engage into a key slot 15 in said shaft, and the shaft is axially slideable in bearings in the side frames 10 to bring the heads into alternate operative alignment with the anvil blades 55. A coil spring 71 (see Fig. 16) surrounds the shaft 20 70 between the right hand side frame 10 and a collar 72 fixed on the shaft and exerts a tension tending to propel the shaft to the left of the machine. A rock lever 73 is pivoted at 74 on the side frame and its rear 25 end is connected with the collar 72 by a link 75, while its front end is provided with an anti-friction ball roller 76 which is positioned to engage the side of a surface cam 77. By this mechanism the shaft 70 30 is shifted laterally at intervals timed relative to the operations of the anvil arms 26-26'. A transverse stop rod 78 limits the rearward movement of the stapling heads and the distribution of the weight 35 of said heads relative to their supporting shaft 70 is such that the heads are normally retained against the stop rod 78 by gravity and will be returned to such position by gravity when permitted by their operating 40 mechanism. Such operating mechanism comprises the two driving bars or clevis members 28-29 extending across the machine between the side frames in rear of the stapling heads 27 and adapted to cooperate 45 with the mechanism of said heads in a manner to be later described. The clevis members 28-29 have downwardly extending legs 82-83 respectively which are loosely journaled on a transverse rod 84 and at 50 opposite sides of the machine duplicate mechanisms are provided which function in unison to oscillate the clevis members. Each of these mechanisms include a double cam 85 fixed on the shaft 30, (see Figs. 4, 55 14, 15) with anti-friction rollers 86-87 which are carried by arms 88-89, engaging into the respective cam grooves formed on opposite sides of the cam. The arms 60 88-89 are loosely journaled on a cross rod 90 and their upper ends are slotted for adjustable connection with rods 91-92, the rod 91 connecting with the arm 88 and with the respective leg 82 of the clevis member 28, and the rod 92 connecting with the 65 arm 89 and with the respective leg 83 of

the clevis member 29. The formations of the cam grooves of the cam 85 provide for the relative operations of the clevis members 28-29 in proper sequence for the functioning of the stapling heads in the 70 manner to be later explained.

With particular reference to Figs. 6 to 10, the construction and operation of one of the stapling heads 27 will now be described, it being understood that all of 75 said stapling heads are of the same construction and operate in like manner. The upper surface of the stapling head 27 is grooved and seated to slide within the groove is a pair of opposed staple forming 80 plungers 100-101 and seated medially in a deep portion of the groove and slidably between the plungers 100-101 is a staple driver 102, the plungers extending rearwardly beyond the driver when in normal retracted position. The sides of the plungers adjacent the driver are provided with longitudinal grooves 103 of a size substantially the same as the thickness of the wire 85 stock of which the staple is formed and the driver has companion tongues 104 engaging into said grooves 103. The wall of the head adjacent the plunger 100 is apertured to receive the wire stock 105, which is fed by mechanism later described, and the front 90 faces of each of the plungers and of the driver are grooved to maintain the wire and staple against vertical displacement during the forming and driving of the 95 staple. A top plate 106 maintains the plungers and the driver within the groove of the head and has secured thereto journal blocks 107 in which is journaled a rock shaft 108 carrying an arm 109, said arm projecting 100 forwardly and having a downwardly extended nose 110 which serves as a forming block about the rear and side surfaces of 105 which the staple is formed. Said nose 110 has a curved forward surface permitting it to swing upwardly past the assembled signatures and a curved rear surface permitting the driving of the formed staple coincident with the elevation of the forming nose, the 110 curvature of said rear surface coupled with the speed of elevation of the arm 109 coinciding with the driving speed of the staple driver 102. A rearwardly extending arm 111 is attached to one end of the rock shaft 108 and carries a roller 112 which is in position to be engaged by the clevis member 29 115 to elevate the arm 109, the parts being yieldingly maintained in the position shown in Fig. 7, by a coil spring 113 (see Figs. 6 and 9) surrounding the shaft 108 with one 120 end fixed to the body of the head 27 and the other end fixed to the arm 111. The rear portions of the plungers 100-101 and of the driver 102 have transverse grooves 125 adapted to receive the upper ends of normalizing leaf springs 114 which are se- 130

cured at their opposite ends to the body of the head 27.

Considering the wire in position as shown in Fig. 8 and the stapling head retracted as shown in Fig. 4, the forward movement of the clevis member 28 which contacts the plungers 100—101 will rock the entire stapling head until the front face of said head contacts the signatures compiled in rear of the anvil blade 55 as in Figs. 7 and 8. A further forward movement of the clevis member 28 translates both plungers 100—101 in the head, the outer edge of the plunger 100 cutting off the staple length from the wire stock and both plungers bending the opposite ends of the staple length forwardly around the side surfaces of the nose 110, as indicated in dotted lines in Fig. 8, to form the staple, the limbs of the staple seating within the grooves 103 of the plungers 100—101. The clevis member 29 will next be driven ahead of the clevis member 28, first engaging the roller 112 to elevate the nose 110 to free the staple from the straight portion of the rear surface of said nose and bring the rear curved surface thereof adjacent the staple. By further forward movement of the clevis member 29 the plunger 102 and the arm 109 are operated in unison, the nose 110 preventing the medial portion of the staple from buckling and the plunger 102 driving the staple through the compiled signatures and out of the grooves 103 of the forming plungers. As the limbs of the staple are driven through the signatures they engage the curved grooves 56 of the anvil blade 55 and are clinched inwardly against the forward surface of the signature adjacent the anvil blade.

The wire stock 105 is drawn from a spool or any suitable source of supply positioned in such relation to the stapling head as experience may prove most satisfactory. Said wire stock passes beneath a lateral shelf 120 of a wire feeding slide 121 and also beneath a similar lateral shelf 122 of a stationary bracket which is attached to the stapling head. (See Figs. 6 and 9.) Said bracket carries a spring pawl 123 having a toothed edge which engages the wire stock 105, preventing a retrograde movement thereof while at the same time allowing a free inward feed of the wire. A similar wire gripping pawl 124 is carried by the feeding slide 121. The slide is positioned in a groove formed in the front surface of the stapling head 27 (see Fig. 7) and is maintained therein by a plate 126 attached to the head. The plate 126 has forwardly extending ears 127 which extend on opposite sides of the anvil blade 55 during the stapling operation and serve to insure a proper cooperative alignment of the head and anvil. The lower surface of the slide 121 is notched as at 128 and the rounded

head of a feeding bell crank lever 129 engages the notch so that upon a rocking movement of the lever the slide 121 will be translated to feed the wire stock. The lever 129 is pivoted at 130 on a bracket 131 which is attached to the head 27 and the free end of the lever carries a roller 132 which engages the rear edge of the clevis member 29. The roller 132 is adjustable in a slot 133 to regulate the throw of the lever 129 and the roller is maintained in contact with the clevis member 29 by a spring 134 one end of which is attached to the bracket 131, the opposite end being attached to a clip 135 on the roller pivot stud. An adjusting screw 136 limits the outward throw of the lever 129.

Assuming that the stapling heads are in position to first cooperate with the anvils 26, the operation of the machine is as follows.

The picker arms 25 are elevated causing their spring fingers 50 to grip the first signature or section of the pack in the magazine and are then lowered to carry said signature down upon the stop fingers 41 which arrest the downward movement of the signature so that by the continued retraction of the picker arms 25 the spring fingers 50 are disengaged from the signature. The stapling heads are now driven forward and the stapling operation performed by the forward movements of the clevis members 28—29 as previously explained.

During the retraction of the stapling heads the anvils 26 are retracted from behind the clinched staples, moved rearward and then elevated in front of said staples, and in this elevating movement the anvils 26 are moved forward to feed the book along the table as previously explained. Also during the retraction of the stapling heads they are shifted laterally by the lateral shifting of their supporting shaft by the action of the cam 77, to bring the heads 110 into cooperative alignment with the anvils 26^a for a succeeding stapling operation. This sequence is repeated throughout the formation of the entire book, the stapling heads alternately cooperating with the anvils 26—26^a, the picker arms compiling a signature for each stapling operation, and each series of anvils operating alternately for each shift of the stapling heads.

The present invention therefore provides a machine for making a book of any thickness by stapling the sections one to another with staples of uniform length.

I claim:

1. In a machine of the nature disclosed, means for successively assembling book sections, and means for stapling each section as assembled to the preceding assembled section.

2. In a machine of the nature disclosed,

means for successively assembling book sections, anvil members, means for inserting the anvil members between the assembled sections, and means co-operating with the anvil members for stapling each section as assembled to the preceding assembled section.

3. In a machine of the nature disclosed, means for successively assembling book sections, a pair of laterally spaced anvil members, means alternately inserting the anvil members behind the book sections, a staple forming and driving device, and means shifting the said device alternately into co-operative alignment with the anvil members, and means operating said device.

4. In a machine of the nature disclosed, means for successively assembling book sections, means for stapling each assembled section only to the preceding assembled section with each staple offset laterally from

the preceding staple, said means including laterally spaced anvil members, a stapling device shiftable laterally to alternate co-operative alignment with each anvil member, and drive means for the stapling device. 25

5. In a machine of the nature disclosed, means for successively assembling book sections, laterally spaced anvil members, means alternately inserting the anvil members behind the book sections, a stapling device co-operating alternately with each anvil member to staple together one section to the assembled section. 35

Signed at Los Angeles, California, this 29th day of December, 1920.

ELMER E. FREY.
